UNITED STATES PATENT OFFICE.

LINCOLN SMITH, OF NANTIC, CONNECTICUT.

VENDING APPARATUS.

SPECIFICATION forming part of Letters Patent No. 416,512, dated December 3, 1889.

Application filed March 22, 1889. Serial No. 304,289. (No model.)

To all whom it may concern.

Be it known that I, LINCOLN SMITH, of Niantic, in the county of New London and State of Connecticut, have invented a new and Improved Vending Apparatus, of which the following is a full, clear, and exact description.

This invention relates to an apparatus wherein upon the deposit of a coin of predetermined value a quantity of merchandise may be obtained, the invention relating more particularly to an apparatus for dispensing beverages.

The invention consists of certain novel constructions, arrangements, and combinations, to be hereinafter fully described, and specifically pointed out in the claims.

Reference is to be had to the accompanying drawings, forming a part of this specification, in which similar figures and letters of reference indicate corresponding parts in all the views.

Figure 1 is a sectional elevation of my improved vending apparatus. Fig. 2 is a detail sectional view illustrating the construction of the coin-chute and the tripping-lever. Fig. 3 is a cross-sectional view of the slide and its way. Fig. 4 is a sectional plan view of the apparatus, the view being taken on line *xx* of Fig. 1; and Fig. 5 is a detail view illustrating the construction of the slide and the tripping-lever, the parts being represented as they appear when the slide is drawn out.

In constructing such an apparatus as the one forming the subject-matter of this application I provide a case 10, in which there is arranged a way 11, which serves as a support for a slide 12, this slide being mounted upon the way in any proper manner, but preferably being formed with dovetail grooves, which are entered by projections formed upon the way, as is clearly shown in Fig. 3.

To one side of the way 10 I secure a standard 13, upon which there is mounted a tripping-lever 14, said lever being formed with a tooth 15, which enters a recess *a*, formed in the slide, that end of the lever 14 upon which the tooth is formed being heavier than the opposing end, so that the lever normally rests in the position in which it is shown in Fig. 1, and acts to hold the slide 12 against any forward movement. To the forward end of the lever I pivotally connect an arm 18, that is

formed with a recess *b*, the extending end of the arm being normally held against the extending end of the lever 14 by a spring 19, 55 said spring being connected to the lever and to the arm. The recess *b* is so proportioned as to receive and hold a coin of the prescribed value, but to permit of the passage of a coin of less diameter than the one in connection 60 with which the apparatus is designed to operate.

Above the forward end of the lever 14 there is arranged a coin-chute 20, the upper end of said chute leading to a coin-slot 21, while the lower end is so located as to deliver any coin received thereby to the forward end of the lever, the coin resting in the recess *b*, as shown in Fig. 2. The lever 14 is so balanced that the weight of a coin resting as represented in Fig. 3 will throw the forward end of the lever downward, and as the lever so moves downward its tooth 15 will rise from engagement with the slide, and an arm or projection 23, that is formed upon the arm 18, 75 70 will come into engagement with one of a series of teeth *c*, that are formed near the forward end of the slide 12, and as the slide is moved in the direction of the arrow shown in connection therewith in Fig. 4 the arm 18 80 will be moved to the position indicated by dotted lines in said Fig. 4 and the coin will drop downward and into a coin-receptacle *A*, arranged in the lower part of the machine.

The liquid to be dispensed is placed in a tank *B*, or the original package might be placed in the position in which the tank is represented. The tank is provided with a discharge - pipe 25, which leads outward through the case 10, there to be connected 9c with a nozzle 26, beneath which nozzle there is arranged a tray 27. In the pipe 25 there is located a valve 28, which has a stem 29, that is connected to the slide 12 by means of a connecting rod or bar 30, the parts being 95 so arranged that when the slide is in the position in which it is shown in the drawings the valve will be closed; but when the slide is moved outward the valve will be opened and liquid from the tank or receptacle *B* will 100 be free to flow through the pipe 25 and the nozzle 26 to enter any proper receptacle that is placed beneath said nozzle.

To insure the return of the slide after a

given quantity of liquid has been withdrawn from the tank or receptacle B, I secure a plate or flange 31 to the front of the case 10, and in connection with this plate or flange I provide a folding leaf 32, which is hinged to the case and provided with an upwardly-extending projection 33, which normally rests against the forward end of the slide 12, being held in this position by a spring 34; but when the slide is moved outward the leaf will be thrown against the tension of its spring to the position indicated by dotted lines in Fig. 4, thus preventing the removal of the glass or receptacle from beneath the nozzle 26 until the slide is returned to the position in which it is shown in the drawings.

Any liquid which may overflow from the receptacle placed for its reception beneath the nozzle 26 will be delivered from the tray 27 to a receiving-pan 36, that is placed in the lower portion of the case 10.

Although not positively essential, I prefer to provide the apparatus with a water-tank, such as the one shown at C, which water-tank would have a proper faucet located above the tray, as indicated by dotted lines in Fig. 4; and in order that the water and the liquid contained within the tank or receptacle B may be kept at a low temperature, I would arrange an ice-receiving chest D directly above the slide 12, as shown in Fig. 1.

Having thus described my invention, I claim as new and desire to secure by Letters Patent—

1. In a vending apparatus, the combination, with a slide, of a tripping-lever arranged to engage the slide, a recessed arm pivotally connected to the forward end of the tripping-le-

ver, a coin-chute arranged above the forward end of the lever, and a means for throwing the pivotally-mounted arm, substantially as described.

2. The combination, with a slide formed with a recess *a*, of a pivotally-mounted tripping-lever arranged to engage said recess, an arm hinged to the forward end of the tripping-lever, a spring arranged in connection with the arm, a projection extending laterally from the arm to engage projections formed on the slide, and a coin-chute, substantially as described. 50

3. In a vending apparatus, the combination, with a slide, of a tripping-lever arranged in connection therewith, a means for delivering a coin to the tripping-lever, a folding leaf provided with a projection which normally rests against the forward end of the slide, and a spring arranged in connection with said leaf, substantially as described. 55

4. In a vending apparatus, the combination, with a slide, of a tripping-lever arranged in connection therewith, a coin-receiving apparatus arranged in connection with the lever, a liquid-receptacle, a tube or pipe leading therefrom, a faucet or stop-cock located within the tube, connections between the faucet or stop-cock and the slide, a folding leaf provided with a projection which extends into the path of the slide, and a spring arranged in connection with the leaf, substantially as described. 60 65

LINCOLN SMITH.
